UNITED STATES PATENT OFFICE.

WILLIAM H. PUTNAM, OF ROME, NEW YORK.

DESIGN FOR A SIGN-LETTER.

SPECIFICATION forming part of Design No. 20,918, dated July 7, 1891.

Application filed January 19, 1891. Serial No. 378,387. Term of patent 3½ years.

To all whom it may concern:

Be it known that I, WILLIAM H. PUTNAM, a citizen of the United States, residing at Rome, in the county of Oneida and State of New York, have invented and produced a new and original Design for Signs and Letters for Signs, of which the following is a specification, reference being had to the accompanying drawings, forming a part hereof.

10 Figure 1 shows an alphabet of letters constructed according to my design. Fig. 2 shows a sign constructed with my letters. Fig. 3 shows a section of a letter, as "W," in position on an outline of the letter.

15 The leading features of my design or the distinguishing peculiarity consists in making the letter raised or rounded and provided with the wing-shaped projection *a* either on

the lower left-hand corner or the upper right-hand corner, or both, of the respective letters. 20 A second feature consists in providing a circular tab or ear *b*, carried by an arm projecting horizontally from the upper left-hand corner of the letters. A third feature consists in providing a semicircular recess or notch *c* 25 in the right-hand base corner of such letters as have a plain-base face at that corner.

What I claim is—

The design for sign-letters, as herein shown and described. 30

In witness whereof I have affixed my signature in presence of two witnesses.

W. H. PUTNAM.

Witnesses:

EDWIN H. RISLEY,
GEO. E. DENNISON.
